VALVE STRUCTURE

William Alton Ray, North Hollywood, Calif., assignor to General Controls Co., a corporation of California

Original application May 6, 1947, Serial No. 746,409. Divided and this application March 6, 1950, Serial No. 147,856

4 Claims. (Cl. 137—599)

1

This invention relates to a control valve system for gas burners.

This application is a division of an application filed on May 6, 1947, under Serial No. 746,409, and entitled: Safety Push Button Gas Burner Control System, now Patent No. 2,520,961, issued September 5, 1950.

Systems for the control of such burners generally include a pilot burner that usually remains ignited even when the main burner is extinguished.

It is one of the objects of this invention to provide a valve structure that is simple and inexpensive and capable of being used in systems of this character.

This invention possesses many other advantages, and has other objects which may be made more clearly apparent from a consideration of one embodiment of the invention. For this purpose there is shown a form in the drawings accompanying and forming part of the present specification. This form will now be described in detail, illustrating the general principles of the invention; but it is to be understood that this detailed description is not to be taken in a limiting sense, since the scope of this invention is best defined by the appended claims.

Figure 1 is a diagram of a system embodying a valve that incorporates the invention;

Fig. 2 is a sectional view of the valve;

Fig. 3 is a fragmentary, sectional view similar to Fig. 2, but with the parts in an alternate position;

Fig. 4 is a view similar to Fig. 2, illustrating the valve in active position; and

Fig. 5 is a sectional view, taken along plane 5—5 of Fig. 2, some of the elements being shown in partly diagrammatic fashion.

In the present instance, a main burner 1 is shown as supplied with gas fuel by the aid of a pipe or conduit 2. The passage of fuel to the main burner 1 is controlled by a main shut-off valve 3 operated, for example, electromagnetically. Since such valves are well known, it is not necessary to describe the structure thereof in greater detail.

In order to ignite the burner 1 upon opening of the valve 3, use is made of the pilot burner 4 adjacent the main burner 1. This pilot burner 4, when ignited, produces the pilot flame 5.

Upon failure of the pilot flame 5, the valve 3 cannot be opened, thereby preventing escape of unignited fuel from burner 1. How this is accomplished will be described hereinafter.

The pilot burner 4 may be supplied with fuel

2

through a conduit 6, which is independent of the shut-off valve 3. This conduit 6, as shown most clearly in Fig. 2, may be threaded into a wall 7 of the valve body structure 8. This structure defines a sealed chamber 9.

Control of the flow of fuel from the chamber 9 to the pilot burner 4 is effected by the aid of a delicate, electromagnetically operated relay 10 (Figs. 1 and 5). This relay 10 affects a light armature 11 located in the chamber 9. The relay 10 has an energizing coil 12 wound on one leg 13 of the relay core. The other leg 13 of the relay core forms a knife-edge bearing for the armature 11. The armature 11 is urged normally to the unenergized position shown in Figs. 1 and 5 by the aid of a light compression spring 14. In this position, armature 11 closes a jet 15 which is mounted in the wall 16 of the member 8.

20 Body 8 forms the main support for the control valve elements, and is shown in Fig. 5 as providing the walls 7 and 16 with an intermediate wall 17 between the walls. A casing 18 on one side of the structure 8 forms a sealed space around relay 10, and assists in defining the chamber 9. A cover 19 on the other side of walls 7 and 16 serves to close the chamber 9.

When the pilot flame 5 is in existence, the relay 10 is energized by aid of the thermocouple 30 75 that is adapted to be influenced by the flame 5. The armature 11 is then moved to the attracted position illustrated in Fig. 4, uncovering the jet 15. Thus, fuel can pass from chamber 9 through jet 15, passageway 17, and conduit 18. 35 Upon failure of the flame 5, the relay 10 is promptly de-energized, armature 11 is returned to its unattracted position of Fig. 1, and flow of fuel to the pilot burner 4 is interrupted.

Assuming that the system is inactive or in the 40 position of Fig. 1, both the pilot flame 5 and the main flame 19 being extinguished, the main shut-off valve 3 is closed. Assurance that, under such circumstances, valve 3 must remain closed is effected by aid of a circuit control device which 45 operates to open the circuit for valve 3 when the system is in the inactive position.

For this purpose, a contact arm 20 is utilized, and which carries a contact button 21. This contact arm in the inactive position is out of contact with the corresponding stationary contact 22 appropriately mounted on the apparatus.

In order to permit the valve 3 to be opened, it is necessary that contact arm 20 move to the position of Fig. 4, in which contact points 21 and 22 55 are closed; and it is also necessary that a control

device 23, such as a thermostat, or the like, have its contact closed. When both these conditions exist, the circuit for valve 3 is established through a step-down secondary winding 24 of a transformer 25. The primary winding 26 of this transformer is connected to a conventional source of electrical energy. The circuit for the valve 3 thus includes winding 24, contact 21, contact 22, thermostat switch 23, valve 3, back to coil 24. The valve 3 is thus permitted to open, provided the thermostat or other control device 23 is in a position requiring more heat.

Contact arm 20 is urged to the closing position by the aid of a movable wall or diaphragm 27. This diaphragm 27 is clamped at its edges between a lower housing member 28 and the flange 29 shown as formed integrally with the frame 8. This diaphragm forms a movable wall for a pressure chamber 30. Mechanical contact between arm 20 and control diaphragm 27 is effected by the arm 31 forming an extension of arm 20. The upper end of the arm 31 is bowed, and is in contact with the flat disc 32 attached to the lower side of the diaphragm 27.

The arm 31 is connected to one end 33 of a coil spring 36 which is pivoted on a pin 34 mounted on a bracket 35. This bracket 35 is appropriately supported on the base 36¹ of an insulation material which serves to cover an opening in the housing 28. The other end of the spring 36 is restrained by the bracket 35. Spring 36 thus urges the arm 31 in a clockwise direction.

As shown most clearly in Figs. 2, 3, and 4, the contact arm 20 projects downwardly through an aperture in the base 36¹. The contact 22 is supported on a bracket 37 mounted on the lower side of the base 36¹. A sheet metal cover member 38 may be used to house these contacts.

The spring 36 urges the diaphragm 27 upwardly by aid of arm 31. The diaphragm is, however, urged downwardly by the aid of a compression spring 39. The upper end of this spring abuts the lower wall of member 8, and its lower end engages the disc 40 disposed on the upper side of the diaphragm 27.

The force of spring 39 and of spring 36 is such that, when chamber 30 is at atmospheric pressure, the diaphragm 27 remains in the neutral position of Fig. 2, the arm 20 maintaining contact 21 out of engagement with contact 22.

Pressure of the gas fuel is utilized to urge the diaphragm downwardly to cause valve 3 to open. When it is urged downwardly the contacts 21 and 22 are made as shown in Fig. 4, and the valve 3 can open if control device 23 demands more heat.

To conduct fuel under pressure to the chamber 30, use is made of a bleed hole 77 that connects the passage 17 with a recess 41 leading to the chamber 30. This bleed hole 77 is of such small size that an appreciable period must occur before the diaphragm 27 is moved by gas pressure to the active position of Fig. 4. Furthermore, the armature 11 must be in the energized position to uncover the jet 15, since this jet controls the passage of fuel through the port 17 into bleed hole 77. Accordingly, the valve 3 is prevented from opening unless the relay 10 is energized, corresponding to the existence of the pilot flame 5.

Means are provided to initiate the operation of the system when both the pilot flame 5 and the main burner 19 are extinguished. This is accomplished by providing a supplemental valve for 76

the pilot burner 4, and which passes fuel to the pilot burner independently of the position of the armature 11.

The valve in this instance is shown as having a closure 42 cooperating with a seat formed at the upper edge of a recess 43 that intersects the port 17. This closure is carried by a stem 44. When the valve stem 44 lifts, for example, as shown in Fig. 3, fuel can pass from the chamber 9 downwardly past the closure member 42 and to the port 17 and conduit 18 and pilot burner 4. As shown most clearly in Figs. 2, 3, and 4, a port 45 extends from the chamber 9 to the recess 43 to effect this communication.

Normally, the valve closure 42 is urged to closed position by aid of the compression spring 46 which engages the top of the closure member, and which is held in place by hollow screw 47 disposed in the top of frame 8.

The valve stem 44 is adapted to be lifted manually by the aid of a push button 48. This push button 48 is shown as slidably mounted in a boss 49 depending from the casing member 28. The push button carries a headed stem 50. A compression spring 51 urges the push button 48 to the inactive position of Fig. 4, in which the head of stem 50 is urged into contact with the bottom of the casing 28.

When it is desired to open the pilot valve closure 42, the push button is urged upwardly to apply a force against diaphragm 27 thereby ensuring opening of the main valve circuit contacts 21 and 22. Continued movement of the diaphragm 27, by further movement of the push button 48, serves to compress the spring 39 to the position shown in Fig. 3, and ultimately to lift the stem 44.

This upward movement of the push button 48 thus ensures de-energization of the electrical circuit for operating the valve 3. It will also establish contact between a contact 52, carried on the arm 20, and a stationary contact 53. When these contacts are closed, as shown in Fig. 3, an electric igniter 54, such as a spark device, is energized through a step-down transformer 55. This step-down transformer has a primary winding 56. The circuit for this winding is closed through the secondary winding 24 by the contacts 52 and 53.

Upward movement of the diaphragm 27 under the influence of push button 48 is such that the igniter circuit is first established before stem 44 is raised. In order to accomplish this result, the diaphragm 27 carries a hollow sleeve 57 which is slidably guided in the recess 41. This hollow sleeve has one or more radial apertures 58 near its lower end to maintain communication between the recess 41 and the chamber 30.

The sleeve 57 has a threaded extension 59 which passes through the discs 40, 32, as well as the diaphragm 27. By the aid of nut 60 engaging this extension, these parts are clamped together. The push button 48, in its upward travel, contacts the extension 59.

Sleeve 57 serves to guide the movement of the diaphragm 27. Furthermore, the bottom surface 61 of the sleeve ultimately contacts the bottom of the stem 44 to open the pilot burner valve 42.

When the push button 48 is urged upwardly, the igniter contacts 52 and 53 are first established; then, later on, the surface 61 lifts the stem 44 to pass gas to the pilot burner 4. In this way, it is assured that the igniter will be in operation before passage of fuel to the burner 4.

Of course, at the same time, it is assured that the valve 3 is prevented from opening by separation of contacts 21 and 22.

In order to start the system from inactive position, the push button 43 is urged upwardly to the position of Fig. 3, the pilot 4 is lighted; and button 48 is held until the relay 10 is energized. Jet 15 is then uncovered and gas may now pass to the port 17 independently of the closure member 42. Withdrawal of the button 48 then permits the diaphragm 27 slowly to recede to the operative position of Fig. 4. This delay is due to the restricted bleed hole 77 through which the fuel must pass in order to depress the diaphragm 27. In the operative position of Fig. 4, the contacts 21 and 22, controlling energization of valve 3, are established.

A ground connection 63 may be provided for the igniter circuit and for the metal parts of the apparatus.

Relay 10 may be supported appropriately on a wall of the casing 64, as by the aid of a supporting bracket 65 encompassing the upper pole piece 66 of the relay.

The jet 15 is shown in this instance as threaded appropriately into the wall 16 of frame 8. A packing 67¹ and a gland nut 68, threaded on the jet member 15, serve to ensure a seal around the jet member. Furthermore, the compression spring 14 is anchored at its left-hand end on a frame member 69 having an opening 70 through which the armature 11 can extend. This armature has a shoulder which engages the top of frame member 69 to place the armature in operative position. This frame member 69 can be appropriately supported on the lower leg 71 of the core 13.

The operation of the system is clear from the foregoing. In the event of pilot flame failure, the relay 10 is de-energized, armature 11 covers the jet 15, and the pressure in chamber 30 is reduced by escape of gas through the aperture 58, recess 41, bleed aperture 77, port 17, and conduit 18. The apparatus then returns to the inactive position of Fig. 2, providing a complete shut-off for the pilot burner 4, as well as for the main burner 1. Thereafter, initiation of the operation of the system can be performed, as hereinbefore set forth, by operation of push button 48.

Should the gas pressure be greatly reduced, which may lead to dangerous conditions, the system is returned to the inactive, fully shut-off position of Figs. 1 and 2. This occurs because the pressure in chamber 30 would be insufficient to hold contacts 21 and 22 in engagement, and the fuel can pass from chamber 9 through hole 77, jet 15, port 17 and conduit 18 out through the pilot burner 4. Upon shutting off of the jet 15 by the armature 11, any fuel in the chamber 30 can escape through the aperture 58, recess 41, bleed apertures 77, port 17, and conduit 18.

The inventor claims:

1. In a fluid control structure: a valve body having an inlet passage, an intermediate chamber and an outlet passage; said intermediate chamber being in communication with the passages; means in said chamber for closing the outlet passage; said body providing an alternate passage from the chamber to the outlet passage; a movable valve closure for said alternate passage; a movable wall cooperating with a wall of

the valve body, and defining a space; there being a port between the outlet passageway and said space, to pressurize said space; said port being independent of said closure; an operator for the closure including a connection with said movable wall; and means for moving the wall against the pressure in the space, to move said operator for opening said movable valve closure.

2. In a fluid control structure: a valve body having an inlet passage, an intermediate chamber and an outlet passage; said intermediate chamber being in communication with the passages; means in said chamber for closing the outlet passage; said body providing an alternate passage from the chamber to the outlet passage; a movable valve closure for said alternate passage; a movable wall cooperating with a wall of the valve body, and defining a space; there being a port between the outlet passageway and said space, to pressurize said space; said port being independent of said closure; an operator for the closure including a connection with said movable wall; and manual means for moving the wall against the pressure in the space, to move said operator for opening said movable valve closure.

3. In a fluid control structure: a valve body having an inlet passage, an intermediate chamber and an outlet passage; said intermediate chamber being in communication with the passages; means in said chamber for closing the outlet passage; said body providing an alternate passage from the chamber to the outlet passage; a movable valve closure for said alternate passage; a movable wall cooperating with a wall of the valve body, and defining a space; there being a port between the outlet passageway and said space, to pressurize said space; said port being independent of said closure; an operator for the closure including a connection with said movable wall; said wall when moved in one direction serving to move the operator to unseat said closure; means biasing the valve closure to closed position; means normally urging said wall to a position in which the valve closure is left in seated position; and means for moving said wall to unseat the valve closure.

4. In a fluid control structure: a valve body having an inlet passage, an intermediate chamber and an outlet passage; said intermediate chamber being in communication with the passages; means in said chamber for closing the outlet passage; said body providing an alternate passage from the chamber to the outlet passage; a movable valve closure for said alternate passage; a movable wall cooperating with a wall of the valve body, and defining a space; there being a port between the outlet passageway and said space, to pressurize said space; said port being independent of said closure; said body having a bore communicating with the port; a guide sleeve attached to the movable wall and guided in the bore; said valve closure having a stem extending into the sleeve; and means for moving the wall to engage the stem and unseat the valve closure.
